(57) **CLAIM**

I claim the ornamental design for a tracking device, as shown and described.

DESCRIPTION

FIG. 1 is a front perspective view of a tracking device.

FIG. 2 is a front view of the tracking device shown in FIG. 1.

FIG. 3 is a top view of the tracking device shown in FIG. 1.

FIG. 4 is a bottom view of the tracking device shown in FIG. 1.

FIG. 5 is a right side view of the tracking device shown in FIG. 1.

FIG. 6 is a left side view of the tracking device shown in FIG. 1.

FIG. 7 is a front perspective view of a tracking device according to another embodiment of the invention.

FIG. 8 is a front view of the tracking device shown in FIG. 7.

FIG. 9 is a rear view of the tracking device shown in FIG. 7.

FIG. 10 is a top view of the tracking device shown in FIG. 7.

FIG. 11 is a bottom view of the tracking device shown in FIG. 7.

FIG. 12 is a right side view of the tracking device shown in FIG. 7; and,

FIG. 13 is a left side view of the tracking device shown in FIG. 7.

The broken lines having equal segments represent portions of the article that form no part of the claimed design.

1 Claim, 10 Drawing Sheets
